COMBINED BOBBY PIN AND PERFUME PELLET HOLDER

Joan Weiss, 325 E. 77th St., New York, N.Y.

Filed Feb. 28, 1964, Ser. No. 78,818

Term of patent 14 years

(Cl. D86—10)

Fig. 1.

Fig. 2.

Fig. 3.

I claim:

The ornamental design for a combined bobby pin and perfume pellet holder, substantially as shown.
